UNITED STATES PATENT OFFICE.

FRANK M. JOSLIN, OF AMSTERDAM, NEW YORK, ASSIGNOR TO INMAN MANUFACTURING COMPANY, INC., OF AMSTERDAM, NEW YORK, A CORPORATION OF NEW YORK.

PLUNGER LIFTER.

1,414,650.

Specification of Letters Patent.

Patented May 2, 1922.

Application filed March 29, 1920. Serial No. 369,489.

To all whom it may concern:

Be it known that I, FRANK M. JOSLIN, a citizen of the United States, and residing at Amsterdam, Montgomery County, State of New York, have invented certain new and useful Improvements in Plunger Lifters, of which the following is a specification.

This invention relates particularly to mechanism employed for operating the plunger of a box making machine and its primary object is to provide means which are placed under tension as the plunger descends, and which operates to assist in the return movement of the plunger. Specifically it consists in arranging a coiled spring about a shaft which is alternately rotated in opposite directions to raise and lower the plunger, the spring being secured at one end to the shaft and at the other end to a part held in fixed position, so that as the shaft rotates in a direction to lower the plunger, the spring is put under tension which serves to assist rotation of the shaft in the opposite direction and to lift the plunger after the same reaches the lower limit of its movement. The spring also acts as a cushioning means for the plunger as it approaches the end of its downward movement.

With these and other objects in view the invention is embodied in the mechanism hereinafter described and illustrated in the accompanying drawings, in which—

Fig. 1 shows a side elevation of a mechanism to which the invention is adapted to be applied, certain parts being shown in section;

Fig. 2 shows a front elevation of that portion of the machine to which the present invention is applied;

Fig. 3 is a sectional view on the line 3—3 of Figure 4, this view illustrating the manner of attaching the tensioning devices to the plunger operating shaft;

Fig. 4 is a sectional view on the line 4—4 of Figure 2.

Referring to the parts of the mechanism in detail 10 represents the plunger of a box making machine, which is adapted to enter a die 11 for the purpose of shaping the material to form a box. The plunger 10 is supported from a crosshead 12 to which are secured suitable rack bars 13, these rack bars passing through suitable guides 14 rigidly secured to a fixed part of the machine frame.

55 The plunger is caused to reciprocate by the

action of a shaft 15, provided with gears 16, which mesh with the rack bars 13 above referred to. The shaft 15 is caused to rotate in opposite directions by means of the reciprocating rack bar 17, the teeth of which mesh with a gear 18 secured to the shaft 15, said rack bar being held in engagement with the gear by means of a suitable guideway 19. The rack bar 17 is given a reciprocating motion from a crank plate 20 mounted on a shaft 21, which is driven in any suitable manner.

The particular mechanism constituting the subject matter of the present invention comprises a sleeve 22, which is keyed to the shaft 15. A coiled spring 23 surrounds the shaft 15, one end of this spring being suitably secured to the sleeve 22, as by a set screw 24, a sleeve 25 being interposed between the spring and the shaft. A second sleeve 26 is loosely mounted on the shaft 15, and the other end of said coiled spring is secured to this last mentioned sleeve. Means are provided for holding the sleeve 26 in fixed position, such means comprising a casting 27 adjustably mounted upon a fixed part of the machine frame. This casting is provided with a rib 28, in which a rectangular recess is provided. The sleeve 26 carries a rectangular portion 29 which is adapted to fit the rectangular recess in the rib 28 of said casting, the engagement of said parts preventing rotation of the sleeve 26. The sleeve 26 is further provided with a flange portion 30 having openings on its periphery which are intended for the reception of a suitable tool used in placing the coiled spring 23 under the desired tension. The parts of the mechanism just described are suitably housed in a cover 32 secured to the framework of the machine.

To briefly describe the operation of the device, it will be understood that as the shaft 15 is caused to rotate in opposite directions through the action of the rack bar 17, the plunger 10 will be caused to enter and recede from the die 11. Since the coiled spring 23 is fixed at one end to the sleeve 24 which rotates with the shaft, and the other end of the spring is secured in fixed position, the rotation of the shaft in opposite directions will alternately produce increased and decreased tension in said spring. The result is that when the shaft moves in a direction to force the plunger 10 into the die 110

11, the spring is placed under increased tension, which acts to assist the movement of the plunger as it recedes from the die 11, and which also acts as a cushioning means 5 for the plunger as it reaches the lower limit of its movement.

While the invention has been described with specific reference to a box making machine, it is by no means limited to use in 10 that particular connection, but is capable of employment in various relations. It is not to be understood, therefore, that the invention is intended to be restricted to the particular use referred to, nor to the particular details of mechanism which latter may obviously be modified without departing from the spirit of the invention.

Having thus described the invention, what is claimed as new and desired to be secured 20 by Letters Patent is:

1. In a device of the kind described a shaft, means for rotating the same in opposite directions, a reciprocating plunger, means for causing reciprocation of said 25 plunger as said shaft is rotated in opposite directions, a sleeve nonrotatably secured to said shaft, a coiled spring surrounding said shaft and secured at one end to said sleeve, a second sleeve to which the other end of said 30 spring is secured, said second sleeve being rotatably mounted on said shaft, whereby the tension of said spring may be altered, and means for holding said second sleeve in fixed position as said shaft is rotated in opposite directions.

2. In a device of the kind described, a shaft and a frame for supporting the same, means for rotating the shaft in opposite directions, a reciprocating plunger, means for causing reciprocation of said plunger as said 40 shaft is rotated in opposite directions, a sleeve secured to said shaft, a coiled spring surrounding said shaft and secured at one end to said sleeve, a second sleeve to which

the other end of said spring is secured, said 45 second sleeve being loosely mounted on said shaft, a projection on said second sleeve, a member rigidly secured to the machine and provided with a recess for receiving the projection on said second sleeve, whereby rotation of said second sleeve is prevented.

3. In a device of the kind described, a shaft and a frame for supporting the same, means for rotating the shaft in opposite directions, a plunger, a pair of rack bars secured to said plunger and extending transversely of said shaft, pinions nonrotatably mounted on said shaft and engaging said 55 rack bars, a member nonrotatably mounted on said shaft between said rack bars, a coiled spring secured at one end to said member, a second member rotatably mounted on said shaft to which the other end of said coiled spring is secured, and cooperating 60 means on said second member and the frame of the machine for preventing rotation of said second member as said shaft is rotated in opposite directions.

4. In a device of the kind described, a shaft and a frame for supporting the same, 70 means for rotating the shaft in opposite directions, a reciprocating plunger, means for causing reciprocation of said plunger as said shaft is rotated in opposite directions, a member nonrotatably secured to said shaft, 75 a coiled spring supporting said shaft and secured at one end to said member, a second member to which the other end of said spring is secured, said second member being rotatably mounted on said shaft whereby the 80 tension of said spring may be varied, an adjustable device secured to said frame, and cooperating means on said second member and said device for preventing rotation of said second member as said shaft is rotated 85 in opposite directions.

In testimony whereof I affix my signature.
FRANK M. JOSLIN.
